UNITED STATES PATENT OFFICE.

JOHN J. BRADLEY, OF LONDON, ONTARIO, CANADA.

STAPLE-LOCK FOLDING BOX.

1,048,031.

Specification of Letters Patent.

Patented Dec. 24, 1912.

Application filed November 7, 1911. Serial No. 659,074.

To all whom it may concern:

Be it known that I, JAMES J. BRADLEY, a subject of the King of Great Britain, and a resident of the city of London, in the county of Middlesex, in the Province of Ontario, Canada, have invented a new and useful Staple-Lock Folding Box, of which the following is a specification.

This invention relates to a receptacle or case for holding goods or merchandise. And it consists of the improved construction and novel combination of parts of the same as will be hereinafter first fully set forth and described and then pointed out in the claim. Reference being had to the accompanying drawings forming part of this specification wherein:

Figure 1 is a perspective view of a box embodying my invention. Fig. 2 is a detail perspective view of the cover of same, looking at it from the underside. Fig. 3 is a detail perspective view of the bottom looking at it from the upper side of the box. In this view the sides are cut down to the bottom and the front portions of the sides and end are flattened out. Fig. 4 is a detail side view of the staple.

In the accompanying drawings the numeral 21 indicates the top, 22 the sides and 23 the ends of the top of the box.

24 indicates the bottom. 25 the sides and 26 the ends of the bottom of the box.

a, indicate score lines which are formed on the inside of and at the junction of the sides 22 and ends 23 with the top 21 and on the inside and at the junction of the sides 25 and ends 26 with the bottom 24.

27 indicates a diagonal corner slit cut through the material of which the box is formed from the corner of the bottom 24 or top 21 diagonally across to the corner, b, as shown at the right hand side of Fig. 3. This leaves a triangular shaped portion, c, between the score lines, a, on the sides and ends of the box which triangular shaped portion, c, is folded over the side 25 and the end 26 as shown at the left hand side of Fig. 3, and this triangular shaped portion, c, is secured to said side 25 and end 26 by glue or other adhesive material, or by wire stitching or any means found most suitable or convenient. And at the junction of the fold of the side 25 and end 26 where the triangular shaped portion, c, is folded over said side 25 and end 26 there is a narrow opening,

d, which is left clear without being glued or otherwise cemented to the side 25 or end 26, and this portion, c, is slightly cut away or lowered at e.

28 is a staple formed with the legs, f, f¹, and with the saddle, g. When the triangular shaped portions, c, are folded as described, one of the legs, f, of the staple 28 is inserted in the opening, d, and said fold being slightly lowered or cut away at, e, intermediate the scorings —a— and the adjacent end of the side or end, the saddle, g, of the staple 28 lies flush in the upper side of the side or end of the box, so that this box will occupy very little space when shipping or in storage.

This box is readily, easily and instantly put up as follows: The score lines, a, readily and easily distinguish the sides or ends from the top 21 or bottom 24 and said side and end are readily and easily adjusted by means of said score lines, a, at right angles, the long leg, f, is then readily and easily inserted in the opening, d, at one side or end, and the other short leg, f¹, is inserted in the other opening, d, at the other side or end and pressed all the way in when said side and end are securely locked together. The outer sides and ends are secured together in a similar manner and so on, any number of tops 21 and bottoms 24 are readily, easily and instantly set up as desired.

This folding box furnished with a staple for holding the two adjacent openings, d, at each corner closely and securely together, provides a strong and durable box which may be readily, easily and instantly set up, and when in a knockdown position or lying flat occupies very little space, at the same time provides a box which is simple, strong and durable and very inexpensive to make and one that is very efficient in practical use.

Having thus described my invention, I claim:

A box blank having score lines running longitudinally and crosswise dividing said blank into a central portion adapted to become the bottom of the box, side portions to become the sides and ends of the box, and corner portions, a slit cut in each of said corner portions diagonally from the corner of the central portion to the corner of the blank, the portions formed by said slit and score lines being bent over and secured to said side portions and a narrow opening

formed at the junction where said portions are folded over, in combination with a staple adapted to enter said openings in said folded portions, one leg of said staple formed shorter than the other to easily and instantly enter the two adjacent openings of said fold, said folded portions being slightly cut-away at points between the ends and scorings of said side portions adapted to

permit the saddle of said staple to lie flush to with the tops of said sides and ends.

In testimony whereof, I have signed in the presence of the two undersigned witnesses.

JOHN J. BRADLEY.

Witnesses:

P. J. EDMUNDS,
S. HARDY.
